US0D1046037S

(12) **United States Design Patent** (10) **Patent No.:** **US D1,046,037 S**
Chen (45) **Date of Patent:** **** Oct. 8, 2024**

(54) **TOY RACKET**

(71) Applicant: **Xuzhao Chen**, Shantou (CN)

(72) Inventor: **Xuzhao Chen**, Shantou (CN)

(**) Term: **15 Years**

(21) Appl. No.: **29/936,590**

(22) Filed: **Apr. 9, 2024**

(30) **Foreign Application Priority Data**

Mar. 13, 2024 (CN) 202430127604.7

(51) **LOC (14) Cl.** **21-02**

(52) **U.S. Cl.**

USPC **D21/729**
